UNITED STATES PATENT OFFICE

100,347

DESIGN FOR A CASING FOR POWER HACKSAW MACHINES

Dewey E. Gommel, Indianapolis, Ind.

Application February 24, 1936, Serial No. 61,315

Term of patent 14 years

To all whom it may concern:

Be it known that I, Dewey E. Gommel, a citizen of the United States, residing at Indianapolis, Indiana, in the county of Marion, have invented a new, original, and ornamental Design for a Casing for Power Hacksaw Machines, of which the following is a specification, reference being had to the accompanying drawing, forming a part thereof.

Figure 1 is a side elevational view,
Figure 2 a top plan view,
Figure 3 an end elevational view of a casing for power hacksaw machines, showing my new design.

I claim:

The ornamental design for a casing for power hacksaw machines, as shown.

DEWEY E. GOMMEL.
